UNITED STATES PATENT OFFICE

160,918

BASIN STAND

Harry M. Berner, Chicago, Ill., assignor to American Hospital Supply Corporation, Evanston, Ill., a corporation of Illinois

Application October 22, 1948, Serial No. 149,246

Term of patent 14 years

(Cl. D4—2)

To all whom it may concern:

Be it known that I, Harry M. Berner, a citizen of the United States, residing at Chicago, county of Cook, and State of Illinois, have invented a new, original, and ornamental Design for a Basin Stand, of which the following is a specification, reference being had to the accompanying drawing forming a part thereof, in which:

Figure 1 is a perspective view of a basin stand showing my new design; Fig. 2, a top plan view; Fig. 3, a side view in elevation; and Fig. 4, an end view in elevation.

I claim:

The ornamental design for a basin stand, as shown.

HARRY M. BERNER.
